(57) **CLAIM**

The ornamental design for a hockey stick cover, as shown and described.

DESCRIPTION

FIG. 1 is a left side elevational view of a hockey stick cover showing a first embodiment of my new design;
FIG. 2 is a right side perspective view thereof;
FIG. 3 is a top perspective view thereof;
FIG. 4 is a bottom perspective view thereof;
FIG. 5 is a left side perspective view thereof;
FIG. 6 is a right side elevational view thereof;
FIG. 7 is a rear perspective view thereof;
FIG. 8 is a front perspective view thereof;
FIG. 9 is a left side elevational view of a second embodiment of my new design;

FIG. 10 is a right side elevational view thereof;
FIG. 11 is a top perspective view thereof;
FIG. 12 is a bottom perspective view thereof;
FIG. 13 is a left side perspective view thereof;
FIG. 14 is a right side perspective view thereof;
FIG. 15 is a rear perspective view thereof; and,
FIG. 16 is a front perspective view thereof.

The broken lines shown are included for the purpose of illustrating unclaimed conventional stitching and forms no part of the claimed design.
